Attorney

Patented June 30, 1925.

UNITED STATES PATENT OFFICE.

JACKSON B. GUMAER, OF KANSAS CITY, MISSOURI.

TELEPHONE RECEIVER.

Application filed September 18, 1922. Serial No. 588,944.

To all whom it may concern:

Be it known that I, JACKSON B. GUMAER, a citizen of the United States, residing at Kansas City, in the county of Jackson and State of Missouri, have invented certain new and useful Improvements in Telephone Receivers, of which the following is a specification.

This invention relates to telephone receivers and more particularly to a receiver having a diaphragm fixed at the center and movable at the circumference.

An object of the invention is the provision of a receiver of this type in which the diaphragm may be readily adjusted.

A further object is the provision of a cup and central magnet construction which may be readily and quickly assembled.

A further object is the provision of a simple, durable receiver of relatively few parts.

In the accompanying drawings I have shown one embodiment of the invention. In this showing,

25 Figure 1 is a perspective view,

Figure 2 is a central vertical sectional view,

Figure 3 is a horizontal sectional view on line 3—3 of Figure 2,

30 Figure 4 is a similar view on line 4—4 of Figure 2, and,

Figure 5 is a diagrammatic view showing the magnetic circuit or path.

Referring to the drawings, the reference 35 numeral 1 designates the magnetic cup of the receiver which is formed of suitable material preferably steel, in order to retain a high degree of residual magnetism. A central magnet 2 is mounted in the cup. The 40 central magnet is preferably formed of soft magnetic metal such as wrought iron. As shown, the cup is provided with a threaded opening and the lower portion of the central magnet is threaded as at 3 and adapted

45 to be received in the opening in the cup. A diaphragm 4 is mounted on the upper end of the central magnet by a screw or bolt 5. As shown the diaphragm extends over the upper edge of the cup forming an air

50 gap 6.

An electromagnet coil 7 is arranged

around the center magnet, the coil being formed of suitable windings mounted on a base or spool 8 of suitable material. The magnet is insulated from the cup by means 55 of a disk 9 of suitable insulating material which is secured to the base of the cup by screws 10. The spool is secured to this disk by screws 11 which also serve as binding posts. As shown in Figure 4, the ends 12 of 60 the wire are secured to these binding posts and suitable lead wires 13 connected in the main circuit are also secured to these binding posts. These wires pass through a suitable opening 14 in the cup. The upper end of 65 the cup is provided with a threaded portion 15 adapted to receive the usual rubber or composition ear-piece 16.

The operation of the device will be apparent from the foregoing description. The 70 magnet 7 is energized by current from the lead wires 13 forming a magnet flux indicated by the arrows in Figure 5 of the drawings. This flux flows through the center magnet 2, the diaphragm 4 and the walls 75 of the cup 1. Energization of the walls of the cup attracts the free circumferential portion of the diaphragm 4 over the air gap 6 and releases it as the magnet is energized and deenergized. This alternate movement 80 of the diaphragm transmits the sound through the ear-piece 16 in the usual manner. It will be apparent that the size of the air gap may be adjusted by moving the center magnet 2 in the cup and thus 85 changing the position of the diaphragm.

It is to be understood that the form of my invention herewith shown and described is to be taken as a preferred example of the same, and that various changes in the shape, 90 size, and arrangement of parts may be resorted to without departing from the spirit of the invention or the scope of the subjoined claims.

Having described my invention, I claim: 95

1. A telephone receiver comprising an electromagnet, a casing surrounding said magnet, said casing being formed of conducting material to form a path for the magnetic flux, a diaphragm arranged above 100 said casing and spaced from the upper edge thereof, said diaphragm having a fixed cen-

ter and movable edges and a cover arranged on said casing over said diaphragm.

2. A receiver comprising a cup having a threaded opening, a core arranged within said cup, one end of said core being threaded and received in said opening, an electromagnet surrounding said core, and a diaphragm having its center secured to the

other end of said core, the free edges of said diaphragm being disposed adjacent said cup. 10

In testimony whereof I affix my signature in presence of two witnesses.

JACKSON B. GUMAER.
